UNITED STATES PATENT OFFICE.

EDWARD CRAIG, OF ST. JOSEPH, MICHIGAN, ASSIGNOR TO SARANAC AUTOMATIC MACHINE CORPORATION, OF BENTON HARBOR, MICHIGAN, A CORPORATION OF DELAWARE.

METAL-BOUND SHIPPING BOX.

Application filed October 5, 1922. Serial No. 592,535.

To all whom it may concern:

Be it known that I, EDWARD CRAIG, a citizen of the United States, and resident of St. Joseph, Berrien County, Michigan, have 5 invented a certain new and useful Improvement in Metal-Bound Shipping Boxes, of which the following is a specification.

This invention relates to metal bound boxes in general, but more particularly to 10 those which comprise a flexible or foldable blank, and rectangular end walls about which the blank is folded, together with reinforcing cleats and metal binding for the blank.

15 Generally stated, the object of the invention is to provide a novel and improved metal bound shipping box of the foregoing general character, adapted more particularly for shipping oranges or other similar 20 fruits or commodities.

More specifically considered, the object 25 of the invention is to provide a novel and satisfactory construction of box in which the contents may cause the cover to bulge 30 upward, as is the practice in packing oranges and certain other commodities, and whereby the blanks and the end walls can be easily combined by the shipper or user, to form the boxes, whereby the person filling 35 the box may very easily and securely close it by fastening the end portions of the metal binding in place, as will hereinafter more fully appear.

To the foregoing and other useful ends 40 the invention consists in matters hereinafter set forth and claimed and shown in the accompanying drawings in which—

Figure 1 is a perspective of a metal-bound shipping box embodying the principles 45 of the invention, showing the same filled and ready for transportation.

Figure 2 is a perspective of the different elements of the box in separated condition, and illustrating how they are assembled to 50 form the box.

Figure 3 is an enlarged plan view of a section of the metal binding.

Figure 4 is a cross section of said metal binding.

55 As thus illustrated, the invention comprises end walls 1 and 2 each having two of their edges provided with cleats 3 and 4, and these cleats each have a tongue 5 at one

end and a groove 6 at the other end. The foldable blank which forms the bottom and 55 sides of the box is composed of sheets 7, 8 and 9 flexibly connected together by the metal binding 10, the sheets or sections 7 and 9 being provided with cleats 11 and 12 formed with tongue and groove ends to engage 60 and interlock with the similarly formed ends of the cleats 3 and 4 previously mentioned. In this way the end walls 1 and 2 are held in place when the blank is folded around them, and nails or staples 65 or other fastening devices may be inserted, if desired, to hold the parts in these positions while the box is being filled through its open top. A middle wall or partition 70 75 13 is provided to extend transversely of the box at the point about midway of the two ends thereof. Nails or staples can be inserted with a hammer, from the outside, through the sheets 7, 8 and 9 to hold this partition 13 in place.

After the box is filled, as by crowding the oranges in so that they extend above the open top of the box, the cover 14 is then secured in place. This cover comprises a 75 single sheet of veneer, for example, such as 80 the material from which the other sides and the bottom of the box are made. A strip 85 15 of metal binding extends across the cover and may be secured thereto or may be left loose until after the cover is applied to the box. The cover is placed in position and 90 bent down at its ends, and these ends are then secured in place by folding over the end portions of the metal binding 10, and 95 by inserting nails through these end portions and through the cover and into the cleats 3 previously mentioned. Then the end portions of the strip of metal binding 15 are bent down and nails are inserted 100 through the end portions and into the partition 13 previously mentioned, all as shown in Figure 1, thereby providing a strong and comparatively inexpensive shipping package for oranges or other commodities. The setting up of the box is all done from the outside, as it will be seen, and the cover is 105 easily and securely fastened in place when the box is filled.

The metal binding is preferably of the form shown in the drawings, comprising 105 strap metal with the edges 16 thereof bent

upward and around to provide a channel extending longitudinally of the outer surface of each strip of metal. The bottom of this channel is corrugated transversely at 5 17 to provide narrow transverse grooves. This facilitates the insertion of either nails or staples through the binding, inasmuch as the points of the staples or nails will be held against slipping sidewise by the corrugations and the edges 16 of the binding, so that staples or nails can be inserted either by machinery or by hand with a hammer. Furthermore, this binding is very strong and makes the box capable of holding a 10 heavy load without danger of coming apart or breaking. In the manufacture of the different parts of the box, the strips 10 of binding are preferably stapled to the foldable blank, and the strip 15 can be stapled to the 15 cover 14. The shipper or user, however, after the box is filled, may prefer to use ordinary nails in closing the box in the manner described.

Of course, if necessary, instead of inserting nails or staples to hold the box together while being filled, a form can be used in which the box may be held until after it is loaded and closed by the securing of the cover in place. It will be understood, however, that any suitable or desired expedient can be employed for keeping the box parts in their proper positions while the box is being filled and before the cover is fastened down. As stated, the strip 15 can be secured 20 to the cover 14, before the latter is applied to the box, or the strips 15 for the various boxes can be supplied separately and can be simply nailed at their ends to the partition 13 after the box is filled. As previously 25 stated, because of the interlocking of the cleats on the blank with the cleats on the end walls, the nailing of the end portions of the strips 10 through the cover and to the cleats 3, and the nailing of the end portions of the strips 15 to the partition 13, will hold the 30 box together. However, if additional strength is required, nails or staples can be inserted, after the box is loaded, through the bottom 8 into the cleats 4, and at various 35 other points, should this be necessary or desirable. In any event, when either nails or staples are inserted, corrugations 17 facilitate the perforation of the sheet metal, inasmuch as these corrugations cooperate with the edges 16 to keep the points of the nails or staples from slipping sidewise and thereby help to make it possible to drive the nails or staples either by machinery or by hand with an ordinary hammer.

40 It will be seen that the metal strapping comprises a strap which is practically entirely flat on its bottom surface, so that it will lie absolutely flat and tightly hug the outer surface of the box, as shown in Figure 4, and it will be seen that the bottom surface

17 is flat clear across, and that the entire strap will practically lie flatwise and tightly hug the box. In this way, the strap cannot stretch when bent around the box, or when subjected to pressure from within, and it will press in at the corners of the box and be tight all around.

70 Thus it will be seen that the means for forming the blank from which the bottom and sides are made exclude the cover 14 and its transverse attaching member 15, the projecting ends of which attaching member serve to fasten the cover down with more or less bulge at the middle thereof. It will also be seen that the corrugated portion of the binding members, as shown in Figs. 3 and 4, and of the attaching member 15, extends under the folded over edge portions 16 of the strap metal thus formed, this being an easy and satisfactory way to make the strap metal, but the metal binding may be of any suitable known or approved character, inasmuch as the cover which forms no part of the foldable blank may be fastened at its middle by a transverse attaching member having projecting ends of any suitable or desired character. The cover can be entirely removed, when the box is open, and the cover may have any desired degree of upward bulge, within limits, of course, when it is secured in place.

90 What I claim as my invention is—

1. In a metal-bound box structure for oranges or the like, a plurality of sheets and cleats and metal binding members forming 100 a blank, end walls for the box, partition means to divide the box transversely at the middle to form two compartments, when the blank is folded to form the bottom and sides of the box, a separate flexible cover for the top, and cover attaching means including a transverse metal attaching member for the middle of the cover, in the plane of said partition means, with the opposite ends of this attaching member projecting a distance beyond the edge of the cover and serving to fasten down the cover with more or less upward bulge at the middle thereof, and whereby the means to form the blank exclude said cover and said attaching member thereof.

105 2. A structure as specified in claim 1, said attaching member being a metal strap with transverse corrugation to permit stapling or nailing thereof to the box, and said binding member being of similar character for the same purpose, whereby the box may be manufactured by using staples and then closed by using nails.

110 3. A structure as specified in claim 1, said sheets being disposed between the cleats and binding members, and said binding members and attaching member being secured externally to the sheets and cover.

115 4. A structure as specified in claim 1, said

120

cover attaching means including the end gated strap metal having folded over portions of said metal binding members whereby the ends of said cover are fastened down tight on the box.

smooth edge portions, with the corrugated middle portion extending under said edge ¹⁰ portions, whereby the binding and attaching members are prevented from stretching.

5. A structure as specified in claim 1, said binding members and said attaching member being formed of transversely corrugated

EDWARD CRAIG.
